UNITED STATES PATENT OFFICE.

EDWIN JONES, OF CLEVELAND, OHIO.

RELEASE-CLEVIS FOR CAR-COUPINGS.

1,274,057.

Specification of Letters Patent. Patented July 30, 1918.

Application filed September 13, 1917. Serial No. 191,214.

To all whom it may concern:

Be it known that I, EDWIN JONES, a citizen of the United States, residing at Cleveland, in the county of Cuyahoga and State 5 of Ohio, have invented certain new and useful Improvements in Release-Clevises for Car-Couplings; and I do declare the following to be a full, clear, and exact description of the invention, such as will enable 10 others skilled in the art to which it appertains to make and use the same.

My invention relates to improvements in release clevises for car couplers and has for its principal object to provide a simply 15 constructed and inexpensive yet highly efficient and durable clevis which will eliminate the use of complicated arrangements of parts such as those now commonly employed, thus minimizing the liability of 20 breakage and the trouble and cost of repair.

A further object is to provide a clevis which may be used to advantage with the usual release lever without changing the brackets of said lever or altering it in any 25 way.

Yet another and highly important object is to provide a clevis which may be either applied or detached within a few minutes by the railway repairmen having charge of 30 such, without the necessity of sending the car to the shop.

A still further object is to construct the device so that in case of emergency, it may be quickly and easily duplicated, by practically any repairman, thus eliminating the necessity of substituting odd parts as is now often necessary, since some of the clevises used cannot be constructed in the limited time available.

With the foregoing general objects in view, the invention resides in the novel features of construction and unique combinations of parts to be hereinafter fully described and claimed, the descriptive matter 45 being supplemented by the accompanying drawings which form a part of this specification and in which:—

Figure 1 is a perspective view showing one form of the improved clevis in use with the coupler in locked position;

Fig. 2 is a perspective of the clevis detached;

Fig. 3 is a side elevation of Fig. 1 with the connecting bolt in section;

Fig. 4 is a duplicate of Fig. 3 with the exception that it illustrates the manner in

which the clevis releases the locking pin of the coupler;

Fig. 5 is a view similar to Figs. 3 and 4 but illustrating the position of parts with the knuckle lock in lock set position;

Fig. 6 is a detail side elevation showing a slightly different form of construction; and,

Fig. 7 is an end elevation of Fig. 6.

In the drawings above briefly described, 65 the numeral 1 designates a car coupler of well known type, although the improved clevis is also applicable to other makes of couplers. In the type shown, the knuckle 1' has the usual knuckle lock within the 70 coupler head, and a lock release pin 2 is provided as usual, the upper end of said pin having the well known link 3 pivoted thereto. This link has heretofore been connected in numerous ways with the centrally positioned inner arm 4 of the uncoupling lever 5, but practically all of these ways have been acknowledged inefficient and impractical after thorough tests.

Some of the principal faults have been 80 that alterations in the construction and mounting of the uncoupling lever were necessary, and too much time and labor were required in attaching and detaching the clevis when necessary, for any of the well 85 known reasons, such as:

Uncoupling lever bracket broken.

Uncoupling lever bent or broken.

Knuckle lock broken or bent.

Knuckle lock worn out or jammed. 90

Coupler head cracked or worn out of gage.

Draft spring broken or missing.

Draft timber broken or worn out, etc.

These difficulties are entirely overcome by 95 the present device, since no alterations are necessary, the usual uncoupling lever with its central uncoupling arm, and the common brackets 6 for said lever being retained in their original forms; and since the clevis is 100 so constructed as to only require that a common bolt or cotter be removed or inserted when respectively detaching and attaching the device.

In Figs. 1 to 5, the improved clevis 7 is 10 formed of a single length of metal in the form of a vertically elongated U whose arms 8 are formed with a pair of vertically elongated parallel loops 9, the lower end of one loop 9 being closed at 10, whereas the other 11 is substantially open as indicated at 11. By this construction, the end of the device

adjacent the open end 11 of the loop, may be passed through the usual eye 12 of the release pin 2 or the link 3, as the case may be and this having been done, the two loops 9 5 will straddle the free end of the uncoupling arm 4 as shown clearly in Figs. 1 to 5, the usual bolt 13 being passed through said arm and through the loops as shown. When applied, the device will be highly efficient 10 and durable and may easily be detached whenever necessary for making repairs, either to itself or to other parts of the car which require detachment of the clevis. The loops 9 allow for the necessary longitudinal, lateral and vertical movement of 15 the coupler head and the closed lower end of one of these loops, together with the partially closed corresponding end of the other loop, act as supports for the bolt 13 when 20 the coupler is either in locked or unlocked position as will be clear from Figs. 1, 2 and 5.

A slightly different form of the invention is shown in Figs. 6 and 7. In these figures 25 the arms of the clevis 7' are bent to form vertically elongated loops 9' disposed in parallel relation and positioned in planes parallel with that of the body portion of the U, rather than at right angles to such plane as 30 is the case with the form of the device previously described. This modification requires that the uncoupling arm 4' be flattened at its free end as indicated at 4" so that it may pass through the two loops 9' 35 as shown clearly in Fig. 6. When so arranged, a cotter pin or the like 13' will pass through said arm and will have its ends positioned between the loops 9' to hold the clevis in place. By this arrangement, all 40 strain in releasing the coupling pin is placed directly upon the upper ends of the loops 9' rather than upon a bolt, such as 13 of the form previously described. The device thus possesses greater strength than said 45 previous form and for this reason will preferably be employed wherever possible, but the form originally described is also of great advantage since it may be applied to cars of common construction without flattening the uncoupling arm. It is to 50 be understood also that the loops 9' could be spaced sufficiently to receive the uncoupling arm without flattening if found desirable.

One of the loops 9' of the type of the device 55 illustrated in Figs. 6 and 7, is closed at its lower end as shown at 10', whereas the other loop is open at said end so that the clevis may be applied by simply passing it through the eye of the link member 3 as 60 above described. Either form of the device may be bent upon dies or may be cast, or it will be obvious that it may be constructed by a blacksmith, or by any of the yard repair men having charge of repairing the cars

where possible, without sending them to the 65 shop.

I attach great importance, to the fact that the usual brackets 6 are employed without making any changes whatever therein, and similarly no changes are made in the uncoupling lever 5 and its inner arm 4-4', 70 unless it is found necessary to flatten the free end of the latter. This is an easy matter, however, requiring little time before it is applied, but after the arm is once in use, 75 the first described form of the invention will be applied thereto, rather than remove said arm to flatten its free end.

Another advantageous feature is that the loops 9-9' permit the uncoupling lever to 80 turn quite a distance before it starts to pull upon the clevis. Momentum is thus gathered which makes it extremely easy to release a coupling pin which would otherwise give considerable trouble. 85

From the foregoing, taken in connection with the accompanying drawing, it will be obvious that although my invention, in both of its forms, is extremely simple and inexpensive, it will be highly efficient and durable. Since probably the best results are obtained from the specific features of construction shown and described, these features are by preference followed, but I wish it understood that within the scope of the invention as claimed, numerous minor changes 90 may well be made. 95

I claim:—

1. The combination of a railway car, a coupler head having a release pin provided 100 with a horizontal eye, a release arm extending longitudinally above the coupler head and having a horizontal eye, means for raising said arm, and a connecting link between said pin and arm, said link comprising a one 105 piece metal rod bent into the form of a U whose base passes loosely through the eye of said pin, the arms of said U being bent downwardly substantially upon themselves to form a pair of vertically elongated loops, 110 the sides of said loops being located on opposite sides of said release arm and on opposite sides of said eye thereof, and a pin passing through this eye and projecting in opposite directions from said release arm, 115 one of said loops being open at its lower end to permit passage of the link through the release pin eye.

2. A coupler release clevis formed of a single metal rod bent into the form of a 120 vertically elongated U adapted for passage through an eye on the upper end of the release pin, the arms of the U being formed with vertically elongated loops positioned in spaced parallel planes parallel with that of the U, said loops being adapted to receive the coupler release arm, and the lower end of one of said loops being open. 125

3. The combination of a railway car, a coupler head thereof having the usual release pin with an eye at its upper end, an uncoupling lever with its uncoupling arm 5 positioned centrally over said coupler head and formed with an opening, a clevis formed of a one piece metal rod bent into the form of a vertically elongated **U** whose bottom passes through said eye, the arms of the **U** 10 being formed into spaced vertically elongated loops through which said uncoupling

arm passes loosely, and a pin passing through the opening in said uncoupling arm and having its ends received between the two loops.

15

In testimony whereof I have hereunto set my hand in the presence of two subscribing witnesses.

EDWIN JONES.
